UNITED STATES PATENT OFFICE.

ISADORE RAPHIEL, OF CAMPTI, LOUISIANA.

FAUCET.

No. 845,260.

Specification of Letters Patent.

Patented Feb. 26, 1907.

Application filed July 7, 1906. Serial No. 325,133.

To all whom it may concern:

Be it known that I, ISADORE RAPHIEL, a citizen of the United States, residing at Campti, in the parish of Natchitoches and 5 State of Louisiana, have invented a new and useful Faucet, of which the following is a specification.

This invention relates to gates or faucets of that general class employed for drawing or 10 dispensing molasses, syrup, and other viscous liquids.

The object of the invention is to provide means for automatically closing the gate or valve after each drawing operation and means 15 for yieldably supporting the gate in contact with the discharge end of the faucet, thereby to prevent leakage.

A further object is to provide a sectional carrier pivotally mounted for swinging movement on the faucet and provided with a recess for the reception of the gate or valve, the latter being provided with means for limiting the opening and closing movement of said gate.

25 A still further object of the invention is to generally improve this class of devices so as to increase their utility, durability, and efficiency, as well as to reduce the cost of manufacture.

30 With these and other objects in view the invention consists in the construction and novel combination and arrangement of parts hereinafter fully described, and illustrated in the accompanying drawings, it being understood that various changes in form, proportions, and minor details of construction may be resorted to within the scope of the appended claims.

In the accompanying drawings, forming a 40 part of this specification, Figure 1 is a side elevation of a gate or faucet constructed in accordance with my invention. Fig. 2 is a longitudinal sectional view of the same, showing in dotted lines the valve in opened position. Fig. 3 is a top plan view of the gate or valve, and Fig. 4 is a transverse sectional view taken on the line 4-4 of Fig. 2.

45 Similar numerals of reference indicate corresponding parts in all of the figures of the drawings.

The improved device consists of a barrel or nozzle 5, having one end thereof threaded, as indicated at 6, for attachment to a barrel or other liquid-containing vessel, and its opposite end deflected downwardly and provided 55 with a discharge-orifice, the walls of the nozzle

at the discharge-orifice being convexed and provided with lateral extensions 7, forming a continuation of the convex walls of the nozzle or barrel, as shown.

60

Pivots for swinging movement on the barrel or faucet, as indicated at 8, is a carrier, preferably formed in two sections 9 and 10, detachably secured together by screws or similar fastening devices 11. 65 The arms 9 and 10 are bent inwardly, as indicated at 12, and spaced from the adjacent convex face of the nozzle to form a recess 13, in which is seated a gate or valve 14, the latter being curved to conform to the curvature of the discharge end of the nozzle and provided with terminal laterally-extending flanges 14', which bear against the angular portions 12 of the arms, as shown, thereby locking the valve in position on the carrier. 70 The arms 9 and 10 are each provided with a reduced extension 15, having recesses formed therein, which when the arms are assembled, form a longitudinal bore 16, communicating with the recess 13, as shown, and in which is seated a coil-spring 17, which exerts a yieldable pressure on the gate or valve 14, and thus prevents leakage. One end of the spring 16 bears against a plunger 17', while the opposite end thereof engages a follower-block 18, the pressure exerted on the valve 14 through the medium of the plunger 17 being regulated by means of an adjusting-screw 18', threaded in the walls of the extension 15, as shown.

75

Secured to or formed integral with the arms 9 and 10 is an operating-handle 19, by means of which the valve 14 may be moved to opened position, the upward movement of the valve being limited by a pin or lug 20, 80 extending laterally from the concave face of said valve and adapted to engage the walls of a recess 21, formed in the discharge end of the barrel or nozzle, as shown. Pivots for swinging movement in perforated ears 22, formed on the upper edges of the arms 9 and 10, are depending hangers 23, each having one end thereof bent laterally to form a terminal hook 24, adapted to receive the adjacent end of a spring 25. The spring 25 is 85 preferably formed of a single piece of wire, an intermediate portion of which encircles the barrel or faucet 5 with the opposite ends thereof coiled around suitable lugs or projections 26, secured to and depending from the nozzle, as shown, the intermediate coils 27 of the wire being retained in position on

the lugs 26 by disks or washers 28, pierced by screws or similar fastening devices 29. It will thus be seen that by exerting an upward pull on the handle 19 the valve may be moved to open position, so as to permit the molasses or other contents of the containing vessel to flow through the discharge end of the nozzle into a measure or other suitable vessel.

10. When the handle is released, the spring 25 will automatically return the valve to closed position, the downward or closing movement of the valve being limited by engagement of the lug 20 with the adjacent lower wall of the discharge-nozzle, as shown. By having the carrier formed in two or more sections detachably secured together the parts may be readily detached to expose the spring and plunger when the latter needs repairing, 20 while by reason of the pivotal connection between the hangers and the carrier said hangers are free to move laterally as the valve is moved to open and closed position, so as to prevent the valve or gate from binding on 25 the convex face of the nozzle.

The faucets may be made in different sizes and shapes and plated, japanned, or otherwise coated to give the same a neat attractive appearance.

30. From the foregoing description it is thought that the construction and operation of the device will be readily understood by those skilled in the art and further description thereof is deemed unnecessary.

35. Having thus described the invention, what is claimed is—

1. The combination with a discharge-nozzle having a convex face and provided with lateral extensions forming a continuation of 40 said face, a carrier pivotally mounted for swinging movement and having a gate associated therewith, means for yieldably supporting the gate in engagement with the convex face of the discharge-nozzle, means for 45 limiting the opening movement of the gate, hangers pivotally mounted on the carrier,

and a spring embracing the nozzle and engaging the free ends of the hangers for automatically closing the gate.

2. The combination with a discharge-nozzle, of a carrier mounted for swinging movement thereon, a gate associated with the carrier, hangers pivotally mounted on the carrier, and a spring engaging the hangers for automatically closing the gate. 50

3. The combination with a discharge-nozzle, of a carrier pivotally mounted for swinging movement thereon, a gate associated with the carrier, hangers pivotally mounted on the carrier and provided with terminal 60 hooks, and a spring engaging the hooks for automatically closing the gate.

4. The combination with a discharge-nozzle, of a carrier pivotally mounted for swinging movement thereon, a gate supported by 65 the carrier, hangers depending from the carrier, and a spring encircling the nozzle and having its terminals seated in the hangers.

5. The combination with a discharge-nozzle provided with laterally-extending lugs, of 70 a carrier pivotally mounted for swinging movement on the nozzle, a gate supported by the carrier, hangers pivotally mounted on the carrier and provided with terminal hooks, and a spring embracing the nozzle and having 75 its intermediate portion coiled around the lugs and its terminals engaging the hangers.

6. The combination with a discharge-nozzle, of a carrier pivotally mounted for swinging movement thereon and provided with a 80 recess, a gate seated in the recess and provided with laterally-extending arms engaging the carrier, a follower, a spring interposed between the follower and the gate, and a screw for adjusting the tension of the spring. 85

In testimony that I claim the foregoing as my own I have hereto affixed my signature in the presence of two witnesses.

ISADORE RAPHIEL.
